UNITED STATES PATENT OFFICE.

DAVID RENSHAW, OF SYRACUSE, NEW YORK.

IMPROVEMENT IN STEAM-GENERATORS.

Specification forming part of Letters Patent No. 125,907, dated April 23, 1872.

Specification of certain Improvements in Steam-Generators, invented by DAVID RENSHAW, of Syracuse, in the county of Onondaga and State of New York.

Nature and Object of the Invention.

This invention is designed to furnish a cheap, compact, and economical steam-generator, which can be easily cleaned and kept in order; and the said invention consists in the combination of a reverberatory furnace, a steam-drum placed outside of the said furnace, a horizontal section, and flat metal disk-shaped or equivalent sections, each connected to the said horizontal section and the steam-drum, said flat-metal sections having their surfaces upon which the water rests inclined down toward the connection between them and the said horizontal section, the whole being constructed and arranged substantially as hereinafter more fully set forth.

Description of the Accompanying Drawing.

Figure 1 is a front elevation of my steam-generator, the right-hand half of the reverberatory furnace being removed to give a clear view of the internal parts. Fig 2 is a vertical section of the furnace taken through the line *x x*, Fig. 1, and a side elevation of the internal parts. Fig. 3 is a section, partly in perspective, through the middle of one of the flat-metal sections, hereinbefore mentioned.

General Description.

A is a reverberatory furnace, having two grates, *B B*, and a bridge, *C*, between them to support the horizontal pipe *D*. I prefer to make said pipe *D* of cast-iron, and to cast it with projections *a a* thereon, and forming a part of the same casting to receive the flat sections *E*, which are each provided with a connecting portion, *b*, to form joints with the parts *a*, which joints should be surface-joints, firmly bolted together. *E E* are hollow flat cast-iron sections, which are made in the form of a disk, and stay-bolted with bolts *e*, Fig. 3, which are cast in one piece therewith and form a part thereof. Besides the connecting portions *b*, these sections have connections *c* with the

pipes *d*, which are cast with or connected to the steam-drum *F*. I prefer to connect the pipes *c* and *d* inside the furnace, so that any one of the sections *E* may be removed and replaced without disturbing the arch of the furnace. *F* is a steam-drum, which may be a cylinder in the form shown, and may be cast in a single piece, or it may be of wrought-iron. The ends of the horizontal pipe *D* should project outside of the furnace, and be provided with heads *f* properly bolted to them, which may be removed for the purpose of cleaning out any sediment which may fall into the pipes *D* from other portions of the boiler, or which may be formed or deposited therein. The feed-pipe *G* is also attached to one or both ends of the pipe *D*, and one end is supplied with a blow-off cock, *H*. *I* is a pipe, which forms a connection between the pipe *D* and the steam-drum *F* to insure a certain and proper circulation between them. Said pipe should be placed in the wall of the furnace or outside thereof, so as to be removed from the intense heat of the furnace, and is designed to restore the water to its proper level in case of any foaming or undue activity of the water in the sections *E*.

It will be observed, from a careful examination of the construction and combination of parts herein described, that while the form of the sections *E E* is such as to receive the heat from the fire and the radiation from the crown of the furnace in the most economical manner, and to admit of the most perfect circulation of the heat between them at the same time, all the surfaces of these sections upon which the water rests, and upon which sediment may lodge or form, are inclined downwardly toward the openings which connect them to the cylinder, so that any sediment forming in any of these sections *E E* may be drawn off through the cylinder *D*, and by this means the whole boiler may be easily cleaned, while at the same time it affords a very extraordinary amount of heating surface in a very small space.

Claim.

I claim as my invention--
The combination of the reverberatory fur-

nace A, steam-drum F placed outside of the said furnace, horizontal pipe D, and flat disk or equivalent-shaped sections E E, each connected to the said steam-drum F and horizontal pipe D, and having all its surfaces, upon which the contained water rests and upon which sediment can form or deposit, inclined downwardly toward its connection with

the horizontal pipe D, and the whole being constructed substantially as hereinbefore set forth.

DAVID RENSHAW.
